UNITED STATES PATENT OFFICE.

AUGUSTE GREPPY, OF PARIS, FRANCE.

RACKING DEVICE FOR VATS.

1,151,457.

Specification of Letters Patent.

Patented Aug. 24, 1915.

Application filed February 1, 1912. Serial No. 674,743.

To all whom it may concern:

Be it known that I, AUGUSTE GREPPY, a citizen of the Republic of France, residing at 1 Rue Saint-Claude, Paris, in the Republic of France, engineer, have invented a certain new and useful Improved Racking Device for Vats, of which the following is a specification.

This invention relates to improvements in devices which are used for the purpose of drawing off liquids under pressure without bringing them in contact with the air, such devices being more particularly applicable to the fermentation vats for wines. Some of the known devices of this kind comprise a drawing off tube called a draft tube which is slidable through a suitable tubular bung provided with a watertight arrangement the inner end of such bung being closed when such draft tube is withdrawn, by a threaded stopper which is adapted to be screwed into the said tubular bung.

This invention relates to a device of this kind more particularly for the purpose of fitting to the lower or inner end of the draft tube inlet member and cup-shaped stopper, these members being adapted to retain the greater part of the solid substances which might be found in suspension in the liquid to be racked, such stopper being at the same time adapted to be screwed alternately to the inlet member and to the inner end of the tubular bung.

The accompanying drawings show by way of example a vertical section of the racking device according to this invention.

In such drawings, *k* designates the tubular bung secured in the aperture of the vat or other container of the liquid to be racked. Slidable in such bung is the draft tube *e*, the joint around the said tube being made water tight by means of a rubber washer *w* and of a socket *t* screwed into the outer end of the bung, or by any other suitable watertight arrangement.

The inner end of the bung *k* is threaded at the outside of its periphery at *s*. On the inner end of the tube *e* is secured a cylindrical inlet member *n* the diameter of which is not greater than that of the said tube and the bottom of which carries an extension *u* which extends downward and is threaded. The wall of the inlet member is provided with holes *p* and in such holes are secured small tubes *o* which extend downward within the member, their inner orifices being

located at some distance above the bottom of the said member.

The letter *q* designates a cup-shaped stopper the inner wall of which is threaded for the purpose of being screwed onto the inner end *s* of the bung and the edge of which is preferably curved outwardly as shown in the drawings, such edge lying nearly at the level of the orifices *p*. The bottom of the said stopper *q* carries a central boss *v* which is bored and threaded internally for the purpose of being screwed onto the extension *u* of the inlet member. A washer *r* of rubber or other suitable material is placed on the bottom of the cup formed around the boss *v*. As the inner diameter of the cup is greater than the outer diameter of the inlet member, an annular chamber is formed between these parts when the latter are secured together as shown in the drawings.

When the tube *e* is lowered with the cup-shaped stopper *q* screwed onto the inlet member as shown in full lines, and the liquid contained under pressure in the vat is allowed to escape through the tube *e*, such liquid passes above the upper edge of the cup and passes obliquely into the small tubes *o* and then through the tube *e*. If the liquid holds in suspension small solid substances, some of the latter will be sent to the bottom of the cup by reason of the inclination of the same against the wall of the tube near the orifice *p*, and other small solid substances, which may have passed through the small tubes *o*, will fall to the bottom of the inlet member *n*. So the liquid is rid almost completely of the solid substances in suspension.

The drawing off being done, the tube *e* will be lifted up and will be so turned that the cup-shaped stopper *q* will be screwed onto the end *s* of the bung, as shown in dotted lines in the drawings, the washer *r* being brought against the lower edge of the bung to insure the required water-tightness. In continuing to turn the tube *e*, the extension *u* and the cup-shaped stopper will be unscrewed and then the tube *e* and the inlet member *n* can be taken entirely out.

Having thus described my invention, I claim as new and desire to secure by Letters Patent:

1. The combination of a draft tube having an inlet member at its inner end, and a cup-shaped stopper the inner diameter of which is greater than the outer diameter

of the said inlet member, such cup-shaped stopper being adapted to be secured by screwing to the bottom of the inlet member in thus forming an annular chamber around such member, substantially as described and for the purpose specified.

2. A draft tube having an inlet member at its lower end, the orifices of such member having tubular prolongations extending downwardly into the interior.

3. The combination of a draft tube the inner end of which is provided with openings, and has a threaded prolongation and of a cup having a threaded part to engage such prolongation, the said cup being adapted to surround the inner end of the draft tube.

4. The combination of a tubular bung

having its inner end threaded at its periphery, a draft tube adapted to pass through said bung and having an inlet member at its inner end, and a cup-shaped stopper to be secured by screwing to the bottom of the inlet member in thus forming around such member an annular chamber, and the inner wall of the said cup-shaped stopper being threaded for the purpose of being screwed onto the said end of the tubular bung.

In testimony, that I claim the foregoing as my invention I have signed my name in presence of two subscribing witnesses.

AUGUSTE GREPOO.
